CLAIM

The ornamental design for a combined toy tubular beam and block, as shown and described.

DESCRIPTION

FIG. 1 is a front elevational view of a combined toy tubular beam and block showing my new design, the rear elevational view being identical;

FIG. 2 is a left side elevational view thereof, the right side elevational view being identical; and,

FIG. 3 is a top plan view thereof, the bottom plan view being identical.

FIG. 1

FIG. 2

FIG. 3
